CLAIM

The ornamental design for a footwear upper, as shown and described.

DESCRIPTION

FIG. 1 is a perspective view of a footwear upper embodying the new design;

FIG. 2 is a top view thereof;

FIG. 3 is a right side view thereof;

FIG. 4 is a left side view thereof;

FIG. 5 is a front view thereof; and,

FIG. 6 is a rear view thereof.

The even dash-dash lines in the figure views depict stitching, which does not form a part of the claimed design. The bold dash-dash lines in the figure views depict stitching, which does form a part of the claimed design. The dot-dot-dash broken lines in the figure views show features that form no part of the claimed design. Further, the dot-dot-dash broken lines immediately adjacent the solid portions of the design form the boundary of the claimed design, with the broken lines forming no part of the claimed design.
